OVERLOAD CIRCUIT BREAKER

Original Filed Dec. 16, 1929

FIG.1.

FIG.2.

FIG.3.

UNITED STATES PATENT OFFICE

1,978,713

OVERLOAD CIRCUIT BREAKER

George W. Knight, Milwaukee, Wis., assignor, by
me and assignments, to Allen-Bradley Com-
pany, Milwaukee, Wis., a corporation of Wis-
consin

Application December 16, 1929, Serial No. 414,380
Renewed March 21, 1934

21 Claims. (CL 260—33)

This invention relates to overload circuit breakers.

The circuit breaker to which the invention applies in particular has a self-opening switch, a latch secured in a fixed position by a fusible binder to hold the switch closed, and an electric heater to generate heat and fuse the binder.

Such a circuit breaker is disclosed in the co-pending application of Gustav O. Wilms and 10 Panfilo Trombetta, Serial No. 403,988, filed November 1, 1929, which became Patent No. 1,944,832 on January 23, 1934.

An object of the invention is to provide a circuit breaker which will operate instantly 15 upon the passage of a predetermined excessive current.

Another object is to provide an overload circuit breaker which is both thermally and magnetically operable.

20 Another object is to provide an overload circuit breaker having a magnetic blow-out.

Another object is to provide an overload circuit breaker having means to operate the same manually.

25 Another object is to provide a circuit breaker which is compact and efficient.

The invention possesses the advantage of operating instantly upon the passage of a predetermined excessive current and operating after 30 predetermined periods of time upon the passage of less excessive predetermined currents.

Other objects and advantages will appear hereinafter.

According to the invention, an electric coil 35 functions as both a heater to operate the circuit breaker thermally and as a magnet to operate the circuit breaker magnetically.

The invention also provides a manually operated release to trip the latch and to permit the 40 circuit breaker to open and the electric coil may also function as a magnetic blow-out for the self-opening switch.

A circuit breaker embodying the invention is 45 shown in the accompanying drawing in which the views are as follows:

Fig. 1 is a top plan view with the top cover plate omitted.

Fig. 2 is a longitudinal section on the irregular line 2—2 of Fig. 1.

50 Fig. 3 is a bottom plan view with the bottom cover plate omitted.

The circuit breaker mechanism is arranged in and carried by a casing 1 having the top and 55 the bottom thereof closed by cover plates 2 and 3 which are removably attached to the casing 1 by bolts 4.

The casing 1 has switch terminals 5 and 6 arranged upon the outside of the rear wall there- 60 of and electrically connected, respectively, to

stationary spring contacts 7 and 8 arranged upon the inside thereof.

The spring contacts 7 and 8 are engaged by movable contacts 9 and 10 carried by a support 11 which is connected at one end thereof by 66 a pivot 12 to a lug 13 carried by the casing 1.

The movable contact 9 is in continual engagement with the spring contact 7 which repels the same and tends to swing the support 11 upon its pivot 12 and move the contact 10 out 70 of engagement with the spring contact 8.

The contact 10 is normally held in engagement with the contact 8 by a catch 14 which engages a ratchet wheel 15 carried by the support 11. 75

The ratchet wheel 15 is fixed by a fusible binder 16 upon a heat conductor 17 which is secured in and insulated from the support 11 by a heat insulating bushing 18.

Heat generated by an excessive current is 80 transferred by the heat conductor 17 to the binder 16 and fuses the same so that the ratchet wheel 15 may rotate and permit the spring contact 7 to swing the support 11 upon the pivot 12 and move the contact 10 out of engagement with 85 the contact 8.

The circuit breaker thus far described forms no part of the present invention as the same is described and claimed in the copending application of Gustav O. Wilms and Panfilo Trom- 80 betta, Serial No. 403,988, filed November 1, 1929 which became Patent No. 1,944,832 on Jan. 23, 1934.

The catch 14 is pivoted at its rear end upon a stationary bracket 19 to allow it to be moved 85 into and out of engagement with the ratchet wheel 15.

The catch 14 is urged into engagement with the ratchet wheel by a compression spring 20 which is arranged between the catch and the 100 rear wall of the casing.

The forward movement of the catch is limited, when the circuit breaker is open, by a lug 21 which is carried by the catch and abuts the bracket 19. 105

The heat for fusing the binder 16 is generated by a coil of wire 22 which embraces the heat conductor 17 and has the terminals thereof connected to the movable contacts 9 and 10.

The coil 22 is wound upon a core 23 of magnetic material and is so proportioned, relatively to the current normally carried by the circuit breaker, that an excessive current flowing therethrough will generate sufficient heat to fuse the binder 16 at the end of a predetermined period 110 of time, the length of the period of time being inversely proportional to the amount of excess current.

The core 23 has a flange 24 on each end thereof to provide an abutment for an armature 115 120

25 which extends through the support 11 into engagement with the catch 14.

The armature 25 is notched upon each side to receive the bifurcated end of a plate 26 upon which the armature is fulcrumed and which is attached to the support 11 by the pivot 12 to secure the armature in position.

The coil 22 and the core 23 constitute an electromagnet which attracts the armature 25 and 10 which is arranged close to the contacts 8 and 10 to function as a magnetic blow-out therefor.

The upper end of the armature engages the catch 14 and, when the catch is in engagement with the ratchet wheel, it holds the lower part 15 of the armature out of contact with the flanges 24.

When the current flowing through the coil exceeds a predetermined maximum, the magnetic force exerted upon the lower part of the armature draws it against the flanges 24 and swings the armature upon the fulcrum plate 26, thereby causing the upper end of the armature to move the catch out of engagement with the ratchet wheel against the resistance of the spring 20 which has sufficient strength to hold the catch in engagement with the ratchet wheel and thereby prevent the armature from moving until the current flowing through the coil exceeds the predetermined maximum.

30 If the current flowing through the coil is in excess of the normal maximum but below the predetermined maximum, the spring 20 holds the catch in engagement with the ratchet wheel and the heat generated in the coil by the excessive current follows the heat conductor 17 to the fusible binder 16 and fuses it to allow the ratchet wheel to rotate and the circuit breaker to open.

The circuit breaker may also be opened manually by means of a plunger 27 which extends through the front wall of the casing 1 and into engagement with the catch 14.

Pressure applied to the plunger 27 will cause the catch 14 to move out of engagement with the ratchet wheel 15 against the action of the spring 20 and permit the circuit breaker to open.

The support 11 has a part thereof extended through the front wall of the casing and after the circuit breaker has been opened, the same may be reset by pressing this extended part inwardly until the ratchet wheel 15 is engaged by the catch 14 which then holds the contact 10 in engagement with the contact 8 until the circuit breaker is operated again.

55 The invention herein set forth is susceptible of various modifications within the scope of the appended claims.

The invention is hereby claimed as follows:

60 1. A circuit breaker, comprising a self-opening switch, a thermally and magnetically operable latch normally holding said switch closed, and an electromagnet connected in circuit with said switch to operate said latch magnetically and to provide a magnetic blow-out for said switch and to generate heat to operate said switch thermally.

65 2. A circuit breaker, comprising an electric switch, magnetically operated means to cause said switch to open and to provide a magnetic blow-out for said switch, and other manually and thermally operated means to cause said switch to open.

70 3. A circuit breaker, comprising a self-opening switch, a latch normally holding said switch

closed and operable thermally, magnetically and manually to permit said switch to open, and a magnetic blow-out for said switch.

4. A circuit breaker, comprising a self-opening switch, a thermally operable latch normally holding said switch closed, and an electric coil connected in circuit with said switch to generate heat to operate said latch thermally and to function as an electromagnet to operate said latch magnetically and to provide a magnetic blow-out for said switch. 80

5. A circuit breaker, comprising a self-opening switch, a thermally operable latch normally holding said switch closed, an electric coil connected in circuit with said switch to generate heat to operate said latch thermally and to function as an electromagnet to operate said latch magnetically and to provide a magnetic blow-out for said switch, and other means to operate 85 said latch manually. 90

6. A circuit breaker, comprising a self-opening switch, a thermally operable latch normally holding said switch closed, and an electric coil connected in circuit with said switch to function as a heater to operate said latch thermally and as a magnet to operate said latch magnetically and to provide a magnetic blow-out for said switch. 100

7. A circuit breaker, comprising a self-opening switch, a thermally operable latch normally holding said switch closed, an electric coil connected in circuit with said switch to function as a heater to operate said latch thermally and as a magnet to operate said latch magnetically and to provide a magnetic blow-out for said switch, and other means to operate said latch manually. 110

8. A circuit breaker, comprising a self-opening switch, a ratchet wheel movable relatively to said switch and held against rotation by a fusible binder, a catch arranged upon a stationary pivot and normally engaging said ratchet wheel to hold said switch closed, an electromagnet to generate heat and fuse said binder, and an armature to be moved by said magnet to disengage said catch from said ratchet wheel. 115

9. A circuit breaker, comprising a self-opening switch, a ratchet wheel fixed in position by a fusible binder, a catch arranged upon a stationary pivot and normally engaging said ratchet wheel to hold said switch closed, an electromagnet to generate heat and fuse said binder and to provide a magnetic blow-out for said switch, and an armature to be moved by said magnet to disengage said catch from said ratchet wheel. 125

10. A circuit breaker, comprising a self-opening switch, a ratchet wheel movable relatively to said switch and held against rotation by a fusible binder, a catch arranged upon a stationary pivot and normally engaging said ratchet wheel to hold said switch closed, an electromagnet to generate heat and fuse said binder, an armature to be moved by said magnet to disengage said catch from said ratchet wheel, and a manually operable plunger to disengage said catch from said ratchet wheel. 135

11. A circuit breaker, comprising stationary spring contacts, movable contacts to engage said spring contacts, a support to carry said movable contacts biased by one of said spring contacts to move one of said movable contacts out of engagement with another of said spring contacts, a latch on said support to hold said movable contact in engagement with said latter 145 150

- spring contact, and an electric coil arranged to operate said latch either thermally or magnetically in response to an electric current of predetermined value to release said support and allow said movable contact to move out of engagement with said stationary contact. 5
12. A circuit breaker, comprising stationary spring contacts, movable contacts to engage said spring contacts, a support to carry said movable contacts biased by one of said spring contacts to move one of said movable contacts out of engagement with another of said spring contacts, a latch to hold said movable contact in engagement with said spring contact, an electric coil arranged to operate said latch either thermally or magnetically in response to an electric current of predetermined value to release said movable contact and allow said circuit breaker to open, and other means arranged to operate said latch at will. 10
13. A circuit breaker, comprising a casing, a support pivoted in said casing, a heat conductor fixed in said support and heat insulated therefrom, a ratchet wheel fixed on one part of said heat conductor by a fusible binder, stationary spring contacts arranged in said casing for connection in an electric circuit, movable contacts carried by said support and spring biased to open position, a catch normally engaging said ratchet wheel and holding said contacts in engagement, an electromagnet embracing another part of said heat conductor to generate heat and fuse said binder upon the passage of a predetermined current, and an armature to be moved by said magnet upon the passage of a greater current and disengage said catch from said ratchet wheel. 15
14. A circuit breaker, comprising a casing, a support pivoted in said casing, a heat conductor fixed in said support and heat insulated therefrom, a ratchet wheel fixed on one part of said heat conductor by a fusible binder, stationary spring contacts arranged in said casing for connection in an electric circuit, movable contacts carried by said support and spring biased to open position, a catch normally engaging said ratchet wheel and holding said contacts in engagement, an electromagnet embracing another part of said heat conductor to generate heat and fuse said binder upon the passage of a predetermined current, an armature to be moved by said magnet upon the passage of a greater current and disengage said catch from said ratchet wheel, and a manually operable plunger to disengage said catch from said ratchet wheel. 20
15. A circuit breaker, comprising a casing, a support pivoted in said casing, a heat conductor fixed in said support and heat insulated therefrom, a ratchet wheel fixed on one part of said heat conductor by a fusible binder, stationary spring contacts arranged in said casing for connection in an electric circuit, movable contacts carried by said support and spring biased to open position, a catch normally engaging said ratchet wheel and holding said contacts in engagement, an electromagnet embracing another part of said heat conductor to generate heat and fuse said binder upon the passage of a predetermined current and to provide a magnetic blow-out for said switch, and an armature to be moved by said magnet upon the passage of a greater current and disengage said catch from said ratchet wheel. 25
16. A circuit breaker, comprising a self-opening switch, a heat conductor having a latch se- 75
- cured upon one part thereof by a fusible binder to hold said switch closed, an electro-magnet thermally associated with another part of said heat conductor remote from said binder and connected in circuit with said switch to generate heat to be conducted by said conductor to said binder to fuse the same and operate said latch thermally, and an armature to be moved by said magnet to operate said latch magnetically. 80
17. A circuit breaker, comprising a self-opening switch, a heat conductor having a latch secured upon one part thereof by a fusible binder to hold said switch closed, an electro-magnet thermally associated with another part of said heat conductor remote from said binder and connected in circuit with said switch to generate heat to be conducted by said conductor to said binder to fuse the same and operate said latch thermally, an armature to be moved by said magnet to operate said latch magnetically, and other means to operate said latch manually. 85
18. A circuit breaker, comprising a self-opening switch, a heat conductor having a latch secured upon one part thereof by a fusible binder to hold said switch closed, an electro-magnet thermally associated with another part of said heat conductor remote from said binder and connected in circuit with said switch to provide a magnetic blow-out for said switch and to generate heat to be conducted by said conductor to said binder to fuse the same and operate said latch thermally, and an armature to be moved by said magnet to operate said latch magnetically. 90
19. A circuit breaker, comprising a self-opening switch, a heat conductor having a latch secured upon one part thereof by a fusible binder to hold said switch closed, an electro-magnet thermally associated with another part of said heat conductor remote from said binder and connected in circuit with said switch to provide a magnetic blow-out for said switch and to generate heat to be conducted by said conductor to said binder to fuse the same and operate said latch thermally, an armature to be moved by said magnet to operate said latch magnetically, and other means to operate said latch manually. 95
20. A circuit breaker, comprising a switch having a movable contact biased to an initial position, a latch to hold said movable contact in another position, thermally and magnetically operable means to release said latch, and an electromagnet arranged to generate heat and to exert magnetic force to operate said latch releasing means and to provide a magnetic blow-out for said switch. 100
21. A circuit breaker, comprising a switch having a movable contact biased to an initial position, a latch to hold said movable contact in another position provided with a ratchet wheel retained in fixed position by a fusible binder and a pawl engaging said ratchet wheel, and an electromagnet arranged to provide a magnetic blow-out for said switch and associated with said latch to heat and fuse said fusible binder upon the passage of a predetermined current for a predetermined period of time to permit said ratchet wheel to turn and allow said movable contact to return to its initial position and to exert magnetic force upon the passage of a larger predetermined current to disengage said pawl from said ratchet wheel and thereby release said movable contact instantaneously. 105
